UNITED STATES PATENT OFFICE.

PAUL PRIEM, OF HEIDENHEIM, GERMANY, ASSIGNOR TO AMERICAN VOITH CONTACT COMPANY, INC., OF NEW YORK, N. Y., A CORPORATION OF NEW YORK.

WOOD GRINDER.

Original application filed February 24, 1923, Serial No. 621,117. Divided and this application filed December 10, 1923. Serial No. 679,853.

To all whom it may concern:

Be it known that I, PAUL PRIEM, a citizen of the Republic of Germany, and residing at Heidenheim an der Brenz, Germany, 5 have invented certain new and useful Improvements in Wood Grinders, of which the following is a specification.

My invention relates to wood grinders of the mechanical feed type, and the object 10 of my invention is to provide means for so automatically regulating the feed that the pressure of the charge against the stone is maintained substantially uniform, so that the speed and load of the stone may be 15 maintained substantially constant. The regulation of the feed of the charge is accomplished through means automatically responsive to the varying power demands 20 on the motor which drives the stone.

20 The underlying thought is susceptible of embodiment in various forms of equipment, some of which are illustrated in my copending application Serial No. 621,117, filed February 24, 1923, of which the present application 25 is a division.

In the accompanying drawings—

Fig. 1 is a more or less diagrammatic side elevation of an installation in which my invention is embodied in one form; and 30 Fig. 2 is a similar view of a modified construction.

Referring to Fig. 1, I have indicated at 5 an electric motor of constant speed type, which drives the grind stone 6 through any 35 suitable operating connection, such as a belt or chain 7. Associated with the grind stone is a press chamber 8 faced on opposite sides by feed chains 9 and 10 supported on a suitable frame work 11 and serving to advance 40 and press the charge against the stone. At their lower ends the chains pass around the sprockets 12 on the shafts 13, carrying worm wheels 14 which mesh with the worms 15 on shaft 16, which has at one end a bevel gear 17. Meshing with the latter is a co-operating bevel pinion 18 on the shaft of the pulley 19, around which passes a driving belt or chain 20 from the pulley 21. The shaft of the pulley carries a gear 22 45 meshing with a cooperating gear 23 driven by the rotary pump 24 which operates as a fluid motor. The fluid which drives the pump 24 is delivered thereto from a second pump 25 of the same or different type, the

55 pulley 26 for operating which is driven from the constant speed electric motor 5 through a chain or belt 27, although the pump may be driven from a separate source of power. The fluid upon which the pump 25 operates is contained in a tank 28 and 60 is delivered by the pump 25 to the piping 29 through which it passes to the motor pump 24 to actuate the latter, which discharges the fluid again to the tank 28.

Arranged in the piping 29 is a control 65 valve 30, the valve stem 31 of which is connected with a core 32 of the solenoid winding 33 arranged in the circuit of the motor 5. The solenoid core is attached at its upper end to the lever 34, pivoted at 35 and 70 adjustably counter-weighted at 36.

As the current demand of the constant speed motor 5 varies with the load imposed 75 upon the stone 6 by the charge through the press chains 9 and 10, the fluctuation of current varies the position of the solenoid core 32 and thus opens or closes valve 30 by moving the valve stem 31 up or down. When the current demand of constant speed motor 5 increases with the increasing load, the 80 solenoid core 32 moves downwardly, thereby closing the valve 30. When the current demand of the constant speed motor 5 decreases with decreasing load, the solenoid core 32 moves upward, thereby opening 85 the valve 30. In this way, more or less fluid is delivered by the pump 25 to the pump 24. Inasmuch as the latter drives the press chains 9 and 10 it is obvious that 90 variation of the load upon the grind stone causes a variation in the drive of the feed chains through the throttling of valve 30 in accordance with the current demand upon the grind stone driving motor 5.

The same thought is embodied in the construction shown in Fig. 2, in which the drive of the stone 6 is similar to that shown in Fig. 1. Instead of the continuous feed arrangement for advancing the charge against the stone, however, I have here shown associated with the grind stone a series of reciprocating press plungers 37, each working in its independent feed chamber 38 to force its charge of wood blocks 39 against the stone. Each of the plungers is fed forward by a 100 pinion 40 meshing with a rack 41 on the stem of a plunger, the pinion 40 being driven through a chain connection 42; and the

sprocket of the latter being driven by a chain 43 from a sprocket 44 on the shaft of the pulley 45. The pulley 45 is driven through a belt or chain 46 passing around the driving pulley or gear 47 on the shaft 48 of a turbine 49. The gas or fluid which drives the turbine 49 enters through the pipe 50 in which is arranged a valve 51, the stem 52 of which is connected to the solenoid core 32 which, as in Fig. 1, is hung from one end of the lever 34 pivoted at 35 and counterweighted at 36. The winding 33 of the solenoid is arranged in the circuit of the stone driving motor 5.

15 The operation is analogous to that first described. As the load on the stone varies, with consequent variation of the current input to the motor 5, the solenoid core 32 rises and falls and thus opens or closes the 20 valve 51 by moving the valve stem up or down and thus controlling the flow to the press feed turbine 49. The feed of the press is thus varied and the drive of the stone at substantially constant speed and load is secured.

It will be understood that various modifications in detail may be made without departing from what I claim as my invention.

I claim—

30 1. In a wood grinder installation, a grind stone, a motor for driving the same, a press for mechanically feeding a charge of wood blocks against the stone, a feed gear for advancing the press, a fluid driven member for 35 actuating the feed gear, and means automatically operated by variations in the stone drive conditions incident to varying load on the stone, for controlling the supply of fluid to the fluid-driven member by which 40 the feed gear is operated.

2. In a wood grinder installation, a grind stone, a motor for driving the same, a press for feeding a charge of wood blocks against the stone, a feed gear for advancing the press, a rotary pump acting as a motor and driving the feed gear, and means for controlling the fluid pressure on the rotary pump, so as to maintain substantially constant the load on the grind stone. 45

3. In a wood grinder installation, a grind stone, a motor for driving the same, a press for mechanically feeding a charge of wood blocks against the stone, a feed gear for advancing the press, a rotary pump acting as a motor and driving the feed gear, a second 50 rotary pump, means for driving the same to produce fluid pressure, a piping between the two pumps, and means for controlling the fluid pressure in said piping to maintain substantially constant the load on the grind stone. 55

4. In a wood grinder installation, a grind stone, a motor for driving the same, a press for mechanically feeding a charge of wood blocks against the stone, a feed gear for advancing the press, a rotary pump acting as a motor and driving the feed gear, a second rotary pump, means for driving the same to produce fluid pressure, a piping between the two pumps, a tank from which the fluid is 70 taken by one of the pumps and to which the fluid is returned by the other pump, and means for controlling the fluid pressure in the piping between the pumps, so as to maintain substantially constant the load on the 75 grind stone. 85

In testimony whereof I have signed my name to this specification.

PAUL PRIEM.
